CLAIM

The ornamental design for a spanner beam hanger, as shown and described.

DESCRIPTION

FIG. 1 is a perspective view of a spanner beam hanger showing my new design, the broken line portion of the view representing the end of a beam for illustrative purposes only;

FIG. 2 is a front elevational view of the hanger;

FIG. 3 is a side elevational view of the hanger;

FIG. 4 is a rear elevational view of the hanger;

FIG. 5 is a top plan view of the hanger; and

FIG. 6 is a bottom plan view of the hanger.
